UNITED STATES PATENT OFFICE.

BENJAMIN Y. BOYD, OF CHICAGO, ILLINOIS.

ELECTROTHERAPEUTIC APPARATUS.

No. 926,384.

Specification of Letters Patent. Patented June 29, 1909.

Application filed September 23, 1908. Serial No. 454,435.

To all whom it may concern:

Bé it known that I, BENJAMIN Y. BOYD, a citizen of the United States, and a resident of Chicago, in the county of Cook and State 5 of Illinois, have invented certain new and useful Improvements in Electrotherapeutic Apparatus, of which the following is a full, clear, and exact specification.

My invention is concerned with a novel 10 apparatus designed primarily for treating the male genitalia, although it will be understood that it could be employed in treating other similarly associated organs if desired.

To illustrate my invention I annex hereto 15 a sheet of drawings, in which the same reference characters are employed to designate the same parts in both the figures, of which,—

Figure 1 is a side elevation of my apparatus with parts broken away and in central 20 section; and Fig. 2 is a plan view in section on the line A—A of Fig. 1.

The cup *a*, which is of the proper size and shape to receive the scrotal sack through the open top thereof, is composed of some insulating material, such as glass or hard rubber, 25 and has the conducting wire *b* passed therethrough in any suitable manner, preferably so as to keep the cup liquid tight, and provided with some means of attaching it to a 30 flexible conductor *c*, such for instance as the loop *d*. The other cup *e* is similarly constructed, except that its size and shape are such as to permit it to receive the penis when hanging naturally. It has a similar conducting wire *f* and loop *g* to receive the flexible conductor *h*, which is, of course, secured to the other side of the battery from the conductor *c*, when the current is to be localized on the 35 parts. When it is to be diffused through the

body, the connections may be as shown in dotted lines, where both cups are connected to one side of the battery, and a movable electrode *f'*, indicated diagrammatically, adapted to be applied to the back or any 40 other part of the body may be connected to the other side of the battery. The two cups are connected, preferably by a shallow

trough-like portion *j* and a vertical web *k*, to give rigidity and strength to the structure. The battery employed will, of course, 50 furnish whatever kind and quantity of current is needed.

The operation of the apparatus will be readily apparent: The cups may be filled with plain water, or it may be medicated in 55 one if it is desired to take advantage of the cataphoric action resulting from the electrolysis of the water when a direct current is employed. In a case of varicocele and diminished vigor, a positive galvanic current 60 is sent through the scrotal sack, contracting the varicose veins, and dilating the dorsal and other veins of the penis, thus curing the varicocele and restoring the natural 65 vigor simultaneously. Other methods of use will be readily apparent to those familiar with electrotherapy.

While I have shown and described my invention as embodied in the form which I at present consider best adapted to carry out 70 its purposes, it will be understood that it is capable of modifications, and that I do not desire to be limited in the interpretation of the following claim except as may be necessitated by the state of the prior art. 75

What I claim as new, and desire to secure by Letters Patent of the United States, is:

An apparatus for the purpose described, consisting of a pair of connected cups of insulating material adapted to receive the 80 parts to be treated, and provided with electrode connections so that a current of electricity can be passed into one cup, thence through the contained part to and through the other part, and thence from the other 85 cup.

In witness whereof, I have hereunto set my hand and affixed my seal, this 21st day of September, A. D. 1908.

BENJAMIN Y. BOYD. [L. S.]
